UNITED STATES PATENT OFFICE.

BRADFORD L. WILLIAMS, OF CAMDEN, NEW JERSEY.

MEASURING-CONTAINER FOR SUGAR.

1,110,365.

Specification of Letters Patent. Patented Sept. 15, 1914.

Application filed November 8, 1913. Serial No. 799,867.

To all whom it may concern:

Be it known that I, Bradford L. WILLIAMS, a citizen of the United States, residing at Camden, in the county of Camden and State of New Jersey, have invented a new and Improved Measuring Container Jug for Sugar or like Materials, of which the following is a specification.

My invention has relation to a definite measuring container for sugar or like materials arranged in the spout of the container and in which the removable cap of the container forms the hinge for the definite measuring device of the spout of said container; and in such connection my present invention relates to the particular arrangement of the said device and the hinge connection established by the cap of the container operating in the manner hereinafter explained for the defined purpose.

The nature and scope of my present invention will be more fully understood from the following description taken in connection with the accompanying drawings forming part hereof, in which—

Figure 1, is a vertical central sectional view through the container jug, showing the spout thereof provided with a definite measuring device hinged to the jug by the removable cap of the same, embracing the essential main features of my said invention. Fig. 2, is a top or plan view thereof; and Fig. 3, is a perspective view enlarged of the measuring device removed from the spout 35 of the container jug, to show the detail arrangement thereof.

Referring to the drawing, *a*, is the container jug for containing sugar or like materials with a spout *b*, projecting therefrom and interiorly directly connected with the main body of the jug by an opening *b'*, as clearly illustrated in Fig. 1.

c, is the removable cap of the jug.

d, is the measuring device having a rim or flange *d'*, which when in position in the 45 spout contacts with the neck of the container jug so as to enable the rim of the cap *c*, to engage and form the hinged connection of the said device with the jug.

e', is a catch formed integral with the said 50 device to be engaged by the finger when the said device is in position in the mouth of the spout *b*, for elevating the said device; and *d*', is a projection formed integral with the body *d*', of said device *d*, in position in the 55 said spout, for separating a definite quantity of the contents of the jug, when tilted, so that when the catch *e*', is drawn backward, the said collected definite quantity of the contents can be readily discharged into a 60 suitable receptacle for use, as will be apparent from Fig. 1, of the drawings.

Having thus described the nature and objects of my invention, what I claim as new and desire to secure by Letters Patent is:— 65

A container jug having a removable cap and a spout, in combination with a measuring device seated within the mouth of said spout, said cap forming the hinged connection of said jug with said device, which latter is provided with a catch and with a projection, said projection adapted to separate a definite quantity of material in the said spout in the tilting of said jug, substantially as and for the purposes described. 75

In witness whereof, I have hereunto set my signature in the presence of the two subscribing witnesses.

BRADFORD L. WILLIAMS.

Witnesses:—
